UNITED STATES PATENT OFFICE.

CLINTON A. JOHNSON, OF CHICAGO, ILLINOIS, ASSIGNOR TO WIREBOUNDS PATENTS COMPANY, A CORPORATION OF MAINE.

BOX-STAPLING MACHINE AND PROCESS.

Application filed October 13, 1920. Serial No. 416,654.

To all whom it may concern:

Be it known that I, CLINTON A. JOHNSON, a citizen of the United States, and a resident of Chicago, in the county of Cook, in the 5 State of Illinois, have invented an Improvement in Box-Stapling Machines and Processes, of which the following is a specification.

This invention relates to box stapling machines and processes, and particularly to machines and processes for use in stapling heads, ends, partitions or the like to boxes, crates, packages and the like, and is intended to provide certain improvements contributing 15 to an efficient and practicable box stapling operation.

Another object is to provide a machine and process for forming a staple with its points upstanding within a box, close 20 to the sides thereof and in the corners and driving the same upward into the work from the place where the staple is formed.

The invention will be clearly understood from the following description of one form 25 of machine containing an embodiment of the machine invention and by the use of which the process may be practiced, which machine is shown for illustration in the accompanying drawings.

30 In said drawings:

Fig. 1 is a side elevation of the illustrative machine, parts thereof being broken away and other parts being shown in section to better illustrate the mechanism; said figure 35 also shows a box partly broken away in position to be operated upon.

Fig. 2 is a rear elevation of the illustrative machine.

Fig. 3 is a sectional plan view of the 40 stapling arm and mechanism carried thereby taken on line A—A of Fig. 5.

Fig. 4 is an enlarged rear elevation of the upper part of the machine showing the drive shaft and operating cams.

45 Fig. 5 is a sectional view taken on the line B—B of Fig. 3.

Figs. 6, 7, 8 and 9 are enlarged sectional side elevations of the nose of the stapling arm showing the parts in different phases of 50 operation.

Fig. 10 is a sectional view taken on the line C—C of Fig. 7.

Fig. 11 is a sectional view taken on the line D—D of Fig. 6.

Figs. 12, 13 and 14 are sectional views 55 taken on the line E—E of Fig. 8.

Fig. 15 is a similar view showing only the lifter and cutter—the driver and loop bar being left out for clearness of illustration.

Figs. 16, 17 and 18 are detailed views of 60 the former and cutter, being respectively, a top plan view, a side elevation and an end elevation.

Figs. 19 and 20 are detailed views of the lifter, being respectively, a side elevation 65 and an end elevation.

Figs. 21, 22 and 23 are detailed views of the driver, being respectively, a side elevation, a top plan view and an end elevation.

Fig. 24 is a sectional view taken on the 70 line F—F of Fig. 5.

Fig. 25 is a diagrammatic plan showing a box in different positions on the machine indicating the operation of stapling the box head or end along sides of the box. For 75 clearness of illustration the lid or cover of the box is not shown in this figure or Figure 26.

Fig. 26 is a sectional plan view of the box shown in Fig. 1 taken on the line G—G and 80 showing the end section stapled to the cleats of side sections.

The illustrative machine comprises generally a staple forming and driving mechanism for forming staples and driving them into the work; and clinching or clamping mechanism to hold the box parts in position during the staple driving operation and to clinch the ends of staples which may be driven through 85 the work.

The staple forming and driving mechanism is carried by the arm 2 supported by the frame 1.

A staple driver 5 operates at the end of arm 2 to drive the staples from the nose of 90 the arm which is so formed as to permit the driving of staples close to the box sides and in the corners and to gauge the stapling point from the box sides. The staple is formed at the nose of the arm 2 with its 95 100

legs or points upstanding, and is driven from the place it is formed by the driver 5 upward into the work. The staples are formed from staple wire 4 which is drawn from a suitable reel 6.

As shown in Fig. 5 the staple wire 4 is fed upward through a guide tube 7 through a bearing 8 and passes in front of a former 13 and between a movable loop bar 9 and a bearing 10 said parts being appropriately formed to receive the wire. The upper end of the staple wire 4 when fed to position between the loop bar 9 and the bearing 10 forms one leg of the staple. The wire is then severed by coaction of cutting edges 11 and 12 formed respectively on the under side of the movable former 13 and the upper edge of bearing 8 (see Fig. 11). Immediately following the severing operation the severed end of the wire is bent at right angles beneath the loop bar 9 by the former 13 moving to the left as shown in Fig. 7. The former 13 is then moved upward by a lifter 14 bending the wire upward about the loop bar 9 and forming the other leg of the staple. The driver 5 then rises forcing the movable loop bar 9 out of line through the action of a cam lug 15 (see Figs. 12, 13 and 14), and drives the staple upward into the work.

Thus, it will be noted that in the illustrative machine the staple is formed at the nose of the machine and driven from that point into the work. This is particularly advantageous in that it eliminates the necessity of transferring the staple from the place where it is formed to the place where it is driven.

As shown in Fig. 10 the former 13 reciprocates horizontally between arms 16 and 17 of the lifter 14, arm 17 being so constructed as to accommodate the rearward throw of the former 13. The former is provided with a groove 18 (see Fig. 16) to receive and guide the staple leg when the former 13 is moved horizontally and vertically to complete the formation of the staple. It will be noted that the former 13 first is moved horizontally from the nose of the machine thereby cutting the wire and bending it at right angles, and then is moved vertically forming the second leg of the staple about the loop bar 9. As shown in Fig. 11 the cutting edge 11 of the former 13 is formed at an angle of approximately 45° to the horizontal and the upper edge 12 of bearing 8 is formed to cooperate therewith, to sever the wire when the former 13 is moved to the rear from the nose of the machine.

The staple wire 4 which passes through guide tube 7, bearing 8, in front of the former 13, and between loop bar 9 and bearing 10 is drawn from supply reel 6 by coacting feed and gripping rolls 19 and 20 which are advanced intermittently by a reciprocating

pawl 21 acting upon pins or teeth 22 carried by the wheel 19.

The mechanism described may be actuated from the driving shaft 23 by any suitable means, for example, by the instrumentalities shown in the drawings which will now be described.

The staple wire feed pawl 21 is operated by a lever 21^a pivotally connected to one end of lever 21^b, the other end of which is pivoted to the frame of the machine at 21^c the lever 21^b carrying a roller 21^d contacting with cam 21^e on the shaft 23. The roller 21^d is held against the cam 21^e by means of spring 21^f.

The former 13 is reciprocated horizontally through connecting rod 13^a having a slotted block 13^b at its rear end through which the shaft 23 passes. The block 13^b carries a roller 13^c which contacts with a cam 13^d on the shaft 23 through the action of spring 13^e. Said spring is so arranged as to quickly return the former 13 to its original position, as shown in Fig. 5, when the roller 13^c passes the projection on the cam 13^d. The former 13 is moved vertically through the action of the lifter 14.

The lifter 14 is operated through the fulcrumed arm 14^a connected to the lifter 14 by a pin and slot connection 14^b, and carrying a roller 14^c at its rear extremity which roller contacts with a cam 14^d carried by the shaft 23. The roller 14^c is held in contact with the cam 14^d by means of spring 14^e.

The staple driver 5 is operated by a fulcrumed lever 5^a having its front end connected to the staple driver by a pin and slot connection 5^b, and having its rear end provided with a roller 5^c engaged by a cam 5^d on the shaft 23, said cam having a projection to operate the lever to give the staple driver a quick up stroke and allow its prompt return through the action of spring 5^e.

As will be understood, the cams are so timed and the arrangement of the parts is such that in each cycle or revolution of the shaft 23 the former 13 reciprocates to the rear cutting off a piece of wire for one staple and bending it at right angles under the loop bar 9; the lifter 14 then moves upward raising the former 13 and bending the second leg of the staple upward about the loop bar 9; the driver 5 then moves upward forcing the loop bar 9 out of line and driving the staple upward into the work. The driver 5 then moves downward permitting the loop bar 9 to return to initial position through the action of a spring 24, the former 13 is returned to initial position by the spring 13^e and the staple wire feed mechanism then advances the wire 4 for another staple upward to position between the loop bar 9 and the bearing 10.

Referring to Figures 1, 5 and 24, a clamp-

ing and clinching device to cooperate with the staple driver is carried at the end of arm 3. This device as shown consists of a vertical plunger 30 provided with a rack 31 meshing with a segmental gear 32 pivoted at 33. The segmental gear 32 is provided with an arm 34 to which is pivoted a link 35 connected to a cam lever 36 pivoted at 37 and carrying a roller 38 engaging a cam 39 carried by the shaft 23, said roller being held against said cam by a spring 40. The link 35 is provided between its ends with a turn buckle 41 by means of which it may be lengthened or shortened as may be desired. At each rotation of the shaft 23, the plunger 30 is lowered to cooperate at the proper time with the staple driver to clamp the box head or end during a stapling operation, and to serve as an anvil or clincher to oppose the action of the staple driver and clinch the ends of staples which may be driven through the work. The timing should be such that the plunger clamps the work before the staple is driven. The plunger rises and releases the work after the driving of each staple, enabling the operator to move the box on the stapling arm the required distance for driving the next staple.

The manner of using the machine will be clearly understood by those skilled in the art, and is indicated in Figs. 1 and 25 of the drawings showing an ordinary wire-bound box with foldably connected side and bottom sections provided with cooperating end cleats and heads or ends arranged inside the cleats to be stapled thereto. In performing the stapling operation, the end or head board rests upon the stapling arm as shown in Figure 1, and the operator manipulates the box on said arm while operating the machine successively to drive a row of staples through each cleat; that is to say, through the head or end board along lines which cause the staples to pass into the cleats, and in this operation the tapering nose or terminal of the stapling arm serves as a guide for enabling the operator to position the work and to gauge the staples from the box sides.

Power for operating the machine may be applied in any suitable manner, as for instance, by the power pulley 45 shown in Figure 2, which may be controllably clutched to the shaft 23 by any suitable clutch mechanism.

From the foregoing description it will be understood that one practicable process embodying features of this invention comprises the feeding of a wire to a desired staple driving point in such a manner that the end portion of the wire forms one leg of a staple in position to be driven, severing the wire a distance from its extremity and bending the wire to complete the formation of the staple

at the driving point. Such a process is particularly advantageous for inside box stapling operations in that it permits the forming of a staple in a confined space, for example, close to a box side or in a box corner. Other advantages resulting from the described process will appear to those skilled in the art.

Obviously the present invention is not limited to the specific details of mechanism and procedure described above for illustration and it will be understood that it is not indispensable that all the features of the invention be employed in a single machine or process since the features may be used to advantage separately as defined in the subjoined claims.

Having described the invention what is claimed is:

1. A machine for use in fastening heads, ends, partitions or the like to boxes comprising, in combination, staple-forming mechanism; and means to drive a staple into the work from the place at which it is formed; said forming and driving mechanisms being constructed and arranged to operate within a box and close to the sides thereof. 85

2. A machine for use in fastening heads, ends, partitions or the like to boxes comprising, in combination, means to form a staple with its points upstanding; and means to drive the staple upward into the work from the place at which it is formed; said means being constructed and arranged to operate within a box and close to the sides thereof. 95

3. A machine for use in fastening heads, ends, partitions or the like to boxes comprising an arm having a nose adapted to enter within a box close to the sides thereof, means to form a staple at the nose of said arm; and means to drive the staple into the work from the place at which it was formed. 105

4. A machine for use in fastening heads, ends, partitions or the like to boxes comprising, in combination, staple forming mechanism including means to sever a wire; and means to drive a staple into the work from the place where it is formed; said mechanism and said means being constructed and arranged to operate within a box and close to the sides thereof. 110

5. A machine for use in fastening heads, ends, partitions or the like to boxes comprising, in combination, a staple former including a cutter; and a staple driver adapted to drive a staple into the work from the place where it is formed; said mechanisms being constructed and arranged to operate within a box and close to the sides thereof. 120

6. A machine for use in fastening heads, ends, partitions or the like to boxes comprising, in combination, an arm adapted to reach into a box; means to feed a wire to the nose of said arm; means to form a staple at the nose of said arm; and means to drive the 125

staple into the work from the place at which it was formed.

7. A machine for use in fastening heads, ends, partitions and the like to boxes comprising, in combination, an arm adapted to reach into a box; means to feed a wire to the nose of said arm; means to sever the wire and form a staple at the nose of said arm; and means to drive the staple from the place at which it was formed into the work.

8. A machine for use in fastening heads, ends, partitions or the like to boxes and having an arm adapted to enter a box which comprises, in combination, means to feed a wire to the nose of said arm; means to sever the wire and form a staple with its points upstanding at the nose of said arm; and means to drive the staple from the forming place in the nose of said arm upward into the work.

9. A machine for use in fastening heads, ends, partitions or the like to boxes and having an arm adapted to enter a box which comprises, in combination, means to feed a wire in approximately a vertical line to the nose of said arm whereby the upper end of said wire forms one leg of a staple; means to complete the formation of the staple at the nose of said arm; and means to drive the staple from the place where it is formed.

10. A machine for use in fastening heads, ends, partitions or the like to boxes and having an arm adapted to enter a box which comprises, in combination means to feed a wire in approximately a vertical line to the nose of said arm whereby the upper end of said wire forms one leg of a staple; means to sever and bend the wire to complete the formation of the staple; and means to drive the staple from the place where it is formed.

11. A machine for use in fastening heads, ends, partitions or the like to boxes and having an arm adapted to enter a box which comprises, in combination, means to feed a wire to the nose of said arm in such a manner that the end of said wire forms one leg of a staple; means to complete the formation of the staple at the nose of said arm; and means to drive the staple from the place where it is formed.

12. A machine for use in fastening heads, ends, partitions or the like to boxes and having an arm adapted to enter a box which comprises, in combination, means to feed a wire to the nose of said arm in such a manner that the end of said wire forms one leg of an inverted staple; means to complete the formation of the staple at the nose of said arm including a loop bar, and a cutter and former adapted to sever the wire and bend it about the loop bar; and a driver adapted to drive the staple into the work from the place where it is formed.

13. A machine for use in fastening heads, ends, partitions or the like to boxes and hav-

ing an arm adapted to enter a box which comprises, in combination, means to feed a wire to the nose of said arm in such a manner that the end of said wire forms one leg of an inverted staple; means to complete the formation of the staple at the nose of said arm including a movable loop bar, and a cutter and former adapted to sever the wire and bend it about the loop bar; and a driver adapted to force the loop bar out of line and drive the staple into the work from the place where it is formed.

14. A machine for use in fastening heads, ends, partitions or the like to boxes comprising, in combination, an arm adapted to reach into a box; a staple driver adapted to drive a staple from the nose of said arm; and means to form a staple in position to be driven by said driver.

15. A machine for use in fastening heads, ends, partitions or the like to boxes comprising, in combination, an arm adapted to reach into a box; a staple driver adapted to drive a staple upward from the nose of said arm; and means to form a staple above the driver in position to be driven.

16. A machine for use in fastening heads, ends, partitions or the like to boxes comprising, in combination, an arm adapted to reach into a box; a staple driver adapted to drive a staple from the nose of said arm; means to feed a wire to the driving point of said arm; and means to form a staple from said wire at said point.

17. A machine for use in fastening heads, ends, partitions or the like to boxes and having a stapling arm adapted to operate within a box comprising, in combination, a staple driver adapted to drive a staple from the nose of said arm; means to feed a wire to the nose of said arm in such a manner that the end thereof forms one leg of a staple in position to be driven; means to sever the wire; and means to form the other leg of the staple in position to be driven.

18. A machine for use in fastening heads, ends, partitions or the like to boxes and having a stapling arm adapted to operate within a box comprising, in combination, a staple driver adapted to drive a staple from said arm; means to feed wire to the nose of said arm in such a manner that the end thereof forms one leg of the staple in position to be driven; a staple former and cutter adapted to be moved horizontally to sever the wire and form the head of the staple, and then vertically to form the other leg of the staple in position to be driven.

19. A machine for use in fastening heads, ends, partitions or the like to boxes and having an arm adapted to enter a box which comprises, in combination, means to feed a wire to the nose of said arm in such a manner that the end of said wire forms one leg of an inverted staple; means to complete the

formation of the staple at the nose of said arm including a movable loop bar, and a cutter and former adapted by a horizontal movement to sever the wire and bend it about the loop bar to form the head of the staple and by a vertical movement to form the other leg of the staple. 5

20. In a machine of the class described, mechanism for forming staples comprising, 10 in combination, means to feed a wire in such manner that the end thereof forms one leg of a staple and a cooperating former and loop bar, said former being adapted to move in one direction to form the head of the staple and then in another direction to form the other leg of the staple. 15

21. In a machine of the class described, mechanism for forming staples comprising, 20 in combination, means to feed a wire in such manner that the end thereof forms one leg of a staple and a combination cutter and former movable first in one direction to cut the wire and form the head of the staple and then in another direction to form the other leg of 25 said staple.

22. In a machine of the class described, mechanism for forming and driving staples comprising, in combination, means to feed a wire in such manner that the end thereof 30 forms one leg of a staple in position to be driven; a cooperating former and loop bar, said former being adapted to move in one direction to form the head of the staple and then in another direction to form the other leg of the staple; and a driver to drive the staple from the place where it is formed. 35

23. In a machine of the class described, mechanism for forming and driving staples comprising, in combination, means to feed 40 a wire in such manner that the end thereof forms one leg of a staple; a combination cutter and former movable first in one direction

to cut the wire and form the head of the staple and then in another direction to form the other leg of the staple; and a driver to 45 drive the staple from the place where it is formed.

24. The process of forming staples within a box which is characterized by feeding the 50 end of a wire to a desired staple driving point within the box in such a manner that the end will form one leg of a staple in position to be driven, bending the wire to form the head of the staple, and bending the wire again to form the other leg of the staple. 55

25. The process of forming and driving staples within a box which is characterized by feeding a wire to the driving point in such a manner that the end of the wire will 60 form one leg of a staple in position to be driven, bending the wire in one direction to form the head of the staple, bending the wire in another direction to form the other leg of the staple and driving the staple from the place where it is formed. 65

26. The process of forming staples which is characterized by presenting the end of a wire to a desired staple-driving point in such a manner that the end of the wire will form 70 one leg of the staple in position to be driven, and bending the wire to complete the formation of the staple.

27. In a box stapling machine, mechanism for forming staples comprising means to present the end of a wire to the staple driving point in such a manner that the end portion of the wire will form one leg of the staple in position to be driven and means to 75 bend the wire to complete the formation of the staple. 80

In witness whereof, I have signed my name to this specification.

CLINTON A. JOHNSON.
